HEAT EXCHANGE EQUIPMENT

Daniel Raymond McNeal, Abington, Pa., assignor
to Andale Company, Philadelphia, Pa., a cor-
poration of Pennsylvania

Application May 14, 1937, Serial No. 142,552

2 Claims. (Cl. 257—224)

This invention relates to heat exchange equipment and is particularly concerned with a heat exchanger of the type incorporating a tubular shell and a tube bundle, the two being relatively 5 separable for the purpose of cleaning, replacement of tubes or the like.

Generally considered, the invention is concerned with a novel arrangement of tube sheets and also with features of a flexible joint between 10 a tube sheet and the shell to accommodate relative expansion and contraction of the tubes and shell.

More specifically, the invention provides a 15 novel relationship between elements of the flexible joint and a tube sheet providing for ready removal of the tube bundle including said sheet.

The invention also contemplates employment 20 of two tube sheets at each end of the tube nest, the two sheets being spaced and the space being in communication with a passage providing for 25 testing of the tube joints in both sheets by introduction of fluid under pressure into the inter-sheet space. In association with this feature the invention also has in view connection of the flexible joint above-mentioned with the inner one of 30 the two tube sheets.

Further advantages of the invention including 35 further features of the structure mentioned above will be pointed out more fully herein following 40 a description of the accompanying drawing which illustrates the preferred embodiment of the invention.

The figure of the drawing is a vertical sectional view through an upright heat exchanger incorporating the features of this invention, the mid portion of the shell and tubes being broken out.

The reference numeral 1 indicates a shell and the numeral 2 designates tubes of the nest thereof which extends longitudinally through the shell. 45 At their lower ends the tubes are provided with an inner tube sheet 3 and an outer tube sheet 4, the former being of diameter larger than the diameter of the shell and the latter being of smaller diameter than the first. The shell and, in fact, the entire unit may receive support from a base 5 or the like on which the outer portion of the sheet 3 rests and to which it may be secured by means of studs 6.

The inner tube sheet 3 may be secured to the shell as by means of a ring 7 and studs 8, a packed joint 9 being provided between the sheet 3 and the ring 7.

The upper ends of the tubes are also provided with inner and outer tube sheets 10 and 11, respectively, and in both cases the two tube sheets

are preferably secured to each other in slightly spaced relation, as by a beading 12 formed on one of them, around which beading a welded joint 13 is used.

At the upper end, the inner sheet 10, although 5 of larger diameter than the outer sheet 11, is small enough to fit inside of the shell and to move therein to accommodate relative expansion and contraction of the tubes and shell. This relationship in size of the tube sheet 10 also permits 10 separation of the tube bundle (including its tube sheets) from the shell. In the form illustrated this may be accomplished by disconnecting the studs 8 at the bottom of the unit and then withdrawing the shell upwardly. For this purpose 15 the upper header 14, of course, would first be removed.

Header 14 is secured to the outer tube sheet 11 by means of a ring 15 and studs 16, and this header is provided with a connection 17 which 20 preferably serves as the inlet connection to the tubes.

An outlet header 18 is similarly attached to the lower tube sheet 4, this outlet header being provided with an outlet connection 19. Flow of 25 the heat exchange medium around the tubes and through the shell may be effected by means of the inlet and outlet connections 20 and 21. A number of baffles such as those shown at 22, spaced by means of sleeves 23, may be employed to direct 30 the flow of the heat exchange medium during passage thereof from the inlet connection 20 to the outlet connection 21. These features form no part of the present invention, per se, and they are, therefore, not described in detail herein although 35 it should be noted that in accordance with the invention it is preferable to employ a tube nest or bundle (including tube sheets, baffles, spacers, etc.) which is removable as a unit.

Since the tube sheet 3 at the bottom of the 40 unit is secured to the shell, the upper ends of the tubes and the associated tube sheets are arranged for sliding movement axially of the shell to accommodate expansion and contraction, and with this in mind the present invention provides a 45 flexible joint member 24, preferably of the bellows type and desirably made of thin, annealed steel, one edge of this bellows being secured, as by welding, to the shell as indicated at 25 and the other edge being similarly secured to a ring 26. The 50 ring 26 and the tube sheet 10 are preferably provided with tongue and groove elements 27 adapted to cooperate with packing providing a seal for the shell space. Studs 28 serve to secure the ring 26 to the sheet 10.

5 A port or passage 29 is provided in each of the outer tube sheets 4 and 11, these ports being in communication with the inter-sheet space at each end of the unit and preferably being threaded for convenient attachment of a fluid pressure line for reasons mentioned herebelow.

10 With the foregoing description of structural features in mind, it will be apparent that during operation of the unit heat exchange is effected between the fluid surrounding the tubes and the fluid passing therethrough. The fluid surrounding the tubes flows through the shell from its inlet 20 to its outlet 21, and the other fluid, of course, moves in counterflow from the inlet header 14 15 to the outlet header 18. During normal operation it is contemplated that the passages 29 in the outer tube sheets 4 and 11 shall remain open. In view of this any leakage at the tube joints in either tube sheet is vented to atmosphere, which 20 is in contrast with single sheet arrangements, wherein leakage results in flow of fluid from one side of the unit into the other, for example, from a header into the shell space.

25 The ports 29 in the outer tube sheets may also be employed (when the equipment is not in service) as a means for testing the tightness of the tube joints in both of the tube sheets. To accomplish this a fluid pressure connection (for example, an air supply) may be coupled with one of 30 the ports 29 and fluid pressure introduced into the inter-sheet space. A loose tube joint in the inner tube sheet may then be detected by the discharge of fluid from the inter-sheet space through the inner sheet around a tube and, similarly, a loose tube joint in the outer tube sheet 35 may be detected by the discharge of the testing fluid from the inter-sheet space through the outer sheet around a tube.

40 Further attention is directed to the fact that the flexible joint 24 is provided between the shell 1 and the inner tube sheet 10 in a manner not to interfere with the normal functioning of the port 29 as a vent from the inter-sheet space. The arrangement of the packed joint 27 between the ring 26 and the inner of the two tube sheets 45 is also of importance in permitting independent testing of this joint. Still further the attachment of the flexible joint member to the ring 26,

which, in turn, is attached to the inner sheet 10, also facilitates separation of the tube nest and the surrounding shell. Thus, as hereinbefore mentioned, after disconnection of the studs 8 at the bottom of the unit, removal of the inlet header 14, and disconnection of studs 28 at the top of the unit, the shell may be withdrawn upwardly from the tube nest or bundle.

5 I claim:

1. Heat exchange equipment including a generally upright tubular shell, a nest of tubes in the shell, a tube sheet at the bottom of the shell larger in diameter than the inside diameter of the shell, supporting elements for the device associated with said sheet and providing for support of the device in upright position, a tube sheet at the upper end of the shell of diameter such as to pass through the shell, a header removably secured to the upper tube sheet, the shell being removable upwardly from the tube nest over the upper tube sheet, and a flexible joint between said upper tube sheet and the upper edge portion of the shell including an annular bellows member connected with the shell at one edge and a ring 10 removably attached to the upper tube sheet externally of the header, the other edge of the bellows being connected with said ring, whereby relative separation of the tube nest and shell may be effected by detaching said ring and withdrawing the shell, bellows, and ring upwardly with respect 15 to the tube nest and its associated tube sheets.

2. A heat exchange unit of the tube and shell type having a nest of tubes in the shell, a floating tube sheet at one end of said nest of diameter such as to fit and float within the shell, a second 20 tube sheet adjacent the same end of the tube nest arranged at the outer face of the first sheet, with a space therebetween, the second tube sheet being of smaller diameter than the first, a ring removably attached to the first tube sheet and lying substantially in the plane of the second tube sheet, 25 a header of smaller diameter than the ring for the adjacent ends of the tubes, means securing the header to the second tube sheet, and a flexible joint including a bellows member connected 30 with the ring and also with the adjacent edge portion of the shell.

DANIEL RAYMOND MCNEAL.
